UNITED STATES PATENT OFFICE.

CHARLES B. BAUMGARTNER, OF MANCHESTER, IOWA,

GATE.

1,273,132.

Specification of Letters Patent.

Patented July 23, 1918.

Application filed January 4, 1917. Serial No. 140,521.

To all whom it may concern:

Be it known that I, CHARLES B. BAUMGARTNER, a citizen of the United States, residing in the town of Manchester, county of 5 Delaware, and State of Iowa, have invented certain new and useful Improvements in Gates, of which the following is a specification.

This invention relates to improvements in 10 gates and refers more particularly to a device of that type in which the gate can be vertically raised and lowered while in closed position.

Among the salient objects of the invention 15 are to provide a construction in which the gate can be raised to a predetermined height so as to permit small stock such as hogs and the like to pass under the gate, while the gate is closed to other stock such as cattle 20 and in which when the gate is in such position, it is fixedly locked against being raised or lowered by the stock; to provide in a device of the character described improved means for raising and lowering the gate, 25 the operating mechanism of which cannot be knocked or twisted out of place by the stock, such mechanism preferably consisting of a single cable; to provide in a construction of the character referred to, novel means 30 of locking, taking the form of double locking devices whereby the locking mechanism of the gate can be actuated by either the hand or the foot and which is self-locking when the gate is swung into its closed position; to provide a construction in which the 35 parts of the locking device which are more apt to get out of order, are protected by the frame of the gate itself and in which the various locking mechanisms are so constructed 40 as to be simple in operation and yet effectively perform their function; and in general to provide an improved construction of the character referred to.

In the drawings:

45 Figure 1 is a side elevation of my improved device showing the gate in closed and normal lowered position.

Fig. 2 is a view similar to Fig. 1, but showing the gate in raised position.

50 Fig. 3 is a vertical sectional view taken on line 3—3 of Fig. 1 and looking in the direction of the arrows.

Fig. 4 is a similar view taken on line 4—4 of Fig. 1, and looking in the direction of 55 the arrows.

Fig. 5 is a fragmentary top plan view of the hinged end of the gate on an enlarged scale.

Fig. 6 is a transverse sectional view on an 60 enlarged scale, taken on line 6—6 of Fig. 3 and looking in the direction of the arrows, with parts omitted.

Fig. 7 is a detail view of one of the clamps for the latch member.

Fig. 8 is a detail view of the latch. 65

Figs. 9 and 10 are sectional detail views of the end posts of the gate showing the manner of securing the tie cables of the gate.

Fig. 11 is a vertical sectional elevation of the locking means for the cable. 70

Fig. 12 is a sectional plan view of parts shown in Fig. 11.

Fig. 13 is an elevation partly in section of the latch control mechanism.

Referring to the drawings, 1 and 2 designate the posts at the gate opening. The gate designated as a whole 3 is hinged to the post 1 by the eye-bolts 4 or any suitable hinged construction may be used. This gate consists of end frame members 5 and 6 preferably of U-shaped or channel construction as shown in the drawings, these end frame members or uprights being secured by means of the cross tubes or side members 7 and 8, and intermediate tie wires 9. The gate is supported centrally by means of a pair of channel irons 10 and 11, which are spaced apart to permit the cables or tie rails to pass between them; these channels being held together by the cross members 12. If desired, the tie rails can be tightened by means of the bolts 13 as shown more clearly in Fig. 9. 85

Describing now more in detail the manner in which the gate is so mounted that it can be raised and lowered vertically, top and bottom rails 7 and 8 are pivoted to the posts 5 and 6 by means of pivot pins 14 and 15 respectively. 90

Describing more in detail the manner in 100 which the post 5 is pivotally mounted relative to the eye-bolts 4, through the post is mounted a short shaft or rod 16, held in position by cotter pins 17, this shaft resting on the upper face of the eye-bolts 4. The height of the gate relative to the ground or the fence posts 1 and 2 can be adjusted by means of a plurality of holes or apertures 18, through one of which the shaft 16 extends. This shaft rides frictionally on 110

the upper face of the eye-bolt 4, when the gate is swung into its open or closed position.

The gate can be vertically raised by lifting it up at its front end and can then be locked in any such position of adjustment by means of a cable 19 and the cam actuated clamp 20. One end of the cable is secured as shown at 21 to a threaded bolt 22 at the rear end of the gate and the cable then extends downwardly around the pulley 23, in the form of a sheave, and then upwardly through the lock 20 (in a manner hereinafter described) around the upper pulley 24 and thence downwardly to the rear end of the gate where it is secured at 25 to an adjusting bolt 26. The vertical length of the cable at the front of the gate passes between a pair of jaws 27 and 28; the jaw 28 can be forced inwardly to impinge the wire against the stationary jaw 27 by means of a manually operated cam lever 29, fitted as shown at 30 between two side plates 31, which are secured to the gate. The opposite faces of these jaw members are corrugated as shown at 32, and 33, the action being such that when the jaws are in closed position, they will impinge against the cable 19 and thus lock the gate in its then position of adjustment. The cable can be released by merely swinging the lever 20 outwardly to release the movable jaw member whereupon the gate can be lowered or raised.

Referring now to the latch mechanism for locking the gate in closed position, I preferably provide upper and lower locking members designated 34 and 35 respectively. A pair of spaced clamping plates 36 and 37 are secured to the post 6 by means of bolts 38, the plate being provided for this purpose with ears 39, through which the bolts extend, it being understood, of course, that the plates are apertured to fit over the post. The rear of each of these plates is apertured as shown at 40 to receive a trip rod 41. Between each pair of clamping plates is secured a latch member 42 comprising an apertured body portion 43 and a latch portion 44. A portion of this latch is adapted to fit around the keeper iron 45 secured to the post 2. Each of these latch members is so mounted to have limited and horizontal movement so that they can wipe by the keepers.

Describing now the manner of locking and unlocking the latch members, pivoted to the posts as shown at 46 are a pair of locking dogs 47, it being understood that there is a pair of these dogs for each latch member, each of these dogs having a downwardly projecting, locking tooth 48 adapted to seat in a corresponding recess 49 formed at either side of the latch member. When the locking dog is in its lowered position the teeth engage the recesses 49 and lock the latch member against horizontal movement. The lock-

ing dogs are actuated by the trip rod 41, the trip rod having a pair of T-shaped head members 50 and 51, which project over the rear end of the locking dogs. The trip lever can be operated by hand by pushing down on the upper cross head member 50 or can be operated by foot by pushing down with the foot on the lower cross head 51. This operation swings the dogs out of engagement with the recesses of the latch member whereupon the latter can swing horizontally and thus the jaws of the latch member can wipe by the keeper and the gate swung open. The trip lever is normally held upwardly by means of the spring 53 so that it will not operate the dogs by dropping down. When this trip lever is released, the jaws fall down onto the latch member, which, however, remains in open position until the jaws wipe against the keeper when the gate is closed, whereupon the teeth of the locking dogs pass into engagement with the recesses of the latch and the gate is automatically locked. The locking mechanism is so arranged that when the gate is open, there are no protruding mechanisms or parts to catch the harness or cattle crowding through.

The operation of the device is apparent from the foregoing description and need not be described in detail. The invention is not limited to the details of construction shown except as set forth in the appended claims.

I claim as my invention:

1. In a gate, the combination with an end member pivoted to swing on a vertical axis, of a main body portion pivoted to swing on a horizontal axis whereby it can be raised or lowered to any given position of adjustment relative to the end member, and means for positively locking said body portion in any adjusted position comprising a cable secured to one end of the gate and extending around relatively fixed guides and between clamping members and leverage mechanism for forcing said clamping members into locking engagement with the cable.

2. In a gate, the combination with an end member pivoted to swing on a vertical axis, of a main body portion pivoted to swing on a horizontal axis whereby it can be raised or lowered to any given position of adjustment, and means for positively locking said body portion in said adjusted position, comprising a flexible member movable relative to the gate and leverage operated clamping jaws for locking said flexible member against such movement.

3. In a gate, the combination with an end member pivoted to swing on a vertical axis, of a main body portion pivoted to swing on a horizontal axis whereby it can be raised or lowered to any given position of adjustment, and means for positively locking said body portion to said adjusted position, comprising a cable, guides around which said

cable extends, clamping jaws mounted between said guides and between which the cable passes and a manually operated mechanism for forcing said jaws into locking engagement with the cable.

4. In a gate, the combination with an end member pivoted to swing on a vertical axis, of a main body portion pivoted to swing on a horizontal axis whereby it can be raised or lowered to any given position of adjust-

ment, and means for positively locking said body portion to said adjusted position, comprising a locking mechanism having manually operated clamping jaws, guides mounted above and below said jaws, and a cable 15 extending around said guides and through said jaws and secured to the body portion at points remote from said guides.

CHARLES B. BAUMGARTNER.
